UNITED STATES PATENT OFFICE

LOUIS THOMAS, OF BILLANCOURT, FRANCE, ASSIGNOR TO PAUL VIET, OF BILLANCOURT, FRANCE

APPARATUS FOR THE SUPPLY OF FUEL GAS MIXTURE TO THE CYLINDERS OF INTERNAL COMBUSTION ENGINES

Application filed March 21, 1927, Serial No. 177,158, and in France March 29, 1926.

My invention relates to an apparatus for the supply of a fuel gas mixture, which may be secured to the cylinders of an internal combustion engine for starting purposes, and comprises a very accurate device for regulating the fuel admission orifice as well as the fuel control orifices. In the said gas supply or control apparatus, the valve plate or disk is actuated by means of an annular member 10 which is provided with internal and external projections and is urged against the said valve plate or disk situated in the main body of the apparatus by a spring disposed at the exterior of the driving axle or shaft, this latter being interposed between the said disk provided with projections and an internal flange of the said valve disk, which flange may be separately secured thereto, or between a ring attached by a pin to the said axle and 20 the annular member provided with projections. The said spring may be of the compression type and thus composed of wire wound in a spiral, or of the flexion type, formed of thin strips. The recesses cap nut 25 which effects the tight closing of the upper orifice in the valve disk, is stopped upon the said disk by an axle or pin provided with a head and guided in a thick web or two thin webs formed on the said cap, and the said pin is inserted into one of the holes which are 30 pierced in the said valve disk in the concentric position, or is placed in contact with the angles of a polygon which is formed in a flange of the said valve disk, for example. 35 The said axle is held in place by a split pin, but it might be held by other means, for instance it may be split at the part opposite the head and the two ends separated, so that the latter will abut against the said valve 40 disk and will thus hold it against any longitudinal displacement, or I may employ for this purpose an ordinary split pin. To shorten the apparatus, the above-mentioned rotatable axle may be actuated by means of a joint 45 of the Oldham type comprising a flat transverse portion, and the two flat branches of the main driving shaft and of the said axle of the valve disk are inserted into recesses in a disk having a cross-shaped aperture. 50 The said actuating axle is pierced at the

centre with a bore which serves to reduce its weight and especially to lubricate the several jointed parts concerned in the adjustment of the valve disk as well as the flat part or base of the said disk in friction contact with the main body of the valve apparatus, by withdrawing oil or oil vapor from the engine itself. 55

In the case in which the valve apparatus is situated on the vertical axis, and to obviate any condensation of the liquid fuel upon said valve disk, which would prevent all lubrication of its friction surface, I may provide two annular grooves outside of the friction surface of said disk, one in the interior and one at the exterior, and said grooves are provided with spring-controlled needle valves which have no effect upon the functioning of the valve device but allow any liquid which may condense in the apparatus to be discharged 60 into the engine or to the exterior. 65

The fuel or explosive gas mixture is delivered by a supply conduit and distributed by the valve apparatus to conduits connected to cylinders of the engine which is to be 70 started. It is also the object of the invention to provide means for actuating an auxiliary apparatus, that is the rotation of the central axis of the valve apparatus may be utilized to actuate a tachometer, or on air-planes or 75 the like, a machine gun actuated device. 80

In the appended drawings:

Fig. 1 is a sectional view of the valve apparatus in accordance with the invention.

Fig. 2 is a plan view of the valve disk. 85

Fig. 3 is a sectional view of a valve apparatus with a double row of starting conduits.

Fig. 4 shows a split pin.

Fig. 5 is a plan view of the valve apparatus 90 shown in Fig. 3.

Figs. 6, 7 and 8 show details of the devices for securing the valve disk to its central axle.

Fig. 9 is a sectional view of a valve apparatus of special construction. 95

Figs. 10 and 11 relate to various details.

Fig. 12 is a plan view of the valve apparatus shown in Fig. 9.

Figs. 13 and 14 show modifications in the 100

mounting of the valve plate on its central axle.

Fig. 15 is a general lengthwise section, in which the driving axle forming a check valve is disposed at the end, after the guide.

Fig. 16 is a cross section of the driving axle which forms an abutment for the cap nut.

Fig. 17 is a modification in which the check valve is made double to act in both directions, i. e. inwardly and outwardly.

Fig. 18 is a cross section of the actuating element which has a screwdriver form at the top.

Fig. 19 is a cross section of the inner actuating element forming an abutment for the cap nut.

With reference to the said drawings, Figs. 1 and 3 show two small valve devices in which the valve disk 1 comprises two mortised external projections 2 and an internal flange 3 serving to support a spring 4 which acts upon the apertured annular member or disk 5. In Fig. 1, the cap-shaped nut 6 is locked with reference to the disk 1 by a pin 7 which is guided in one of the holes 9 which are disposed in a concentric circular row upon the said cap or nut 6; the end of said pin is engaged in the circular recesses 8 in the said valve disk (Fig. 2). Since the number of the holes 9 and of the recesses 8 is different, this allows a wide range of adjustment.

The central axle or spindle 10 is pierced with a large bore 11 offering a free passage for the oil or oil vapor from the engine, and thus providing for the oiling of the projections 2 and 12, and the bearing surface 13 of the axle 10, and also, by centrifugal action, the contact surface 14 of the valve disk 1, this being furthered by the vacuum in the conduits 15 of the starter and the chamber 16 of the valve apparatus, during the functioning of the engine.

Fig. 3 relates to a valve apparatus with a double row of conduits for starting purposes, the plug being arrested by a split pin 17 (Fig. 4) whose open ends abut against a polygonal part 18 formed on the outer flange of the valve disk 1 (Fig. 5). The cylindrical compression spring 4 may be replaced by one or more disks 19 (Figs. 6 and 8) whose elastic branches may have the straight form 19 or may be bent over several times as shown at 20 in Fig. 7 to increase the flexibility.

Figs. 9 and 12 relate to a valve apparatus of large size, in which the trimming of the parts is facilitated by disposing the base portion of the said valve disk in a recess which is formed in the bore of said valve disk. The device is arranged as follows. A tapered member 21 (Fig. 10) is placed in contact with the supporting portion 22. By applying the pressure against the part 23 the said member will be straightened out and will fit permanently into the recess, as shown in Fig. 9.

In this valve apparatus, the cap 6 is held

by the wings or lugs 24 of polygonal form, and in each edge is pierced a hole 9 in which may be engaged a stop pin 17 (Fig. 4) which makes contact with the polygonal part 18 whose number of sides differs from the number provided on the cap 21. The said apparatus, which herein occupies the vertical position, comprises two grooves 25 and 26 which eliminate—by the needle valves 27 and 28—any liquid fuel which may have condensed in the supply chamber 16.

Fig. 13 shows a further modification, in which the spring 4 abuts at one end against a washer 29 which is pinned to the main axle or spindle, and at the other end against a notched disk 5 which is in direct contact with the disk 1 by means of its separately secured base.

Fig. 14 represents a cap 6 which is secured to the valve disk 1 by the split pin 30 inserted into holes which are pierced concentrically and at the same radial distance in the cap 6 and the valve disk 1, employing however a different number of holes in the two parts so as to provide for a wide range of adjustment.

In all these figures, the device is actuated by means of flat parts formed on the driving shaft 32 and on the axle 10 of the apparatus, these flat parts being drawn forward by means of the flat disk 31 pierced with a cross-shaped aperture (Fig. 11). The fluidtightness of the cap, which is herein obtained by a packing member 33 interposed between the disk 1 and the cap 6 in the end of the latter, might be obtained by placing the said packing member 33 under the nut and between the base of said nut and the flange 18 extending outwardly of the disk 1.

Referring to Figs. 16 to 19, the several parts are disposed as follows. The driving axle 41, which is externally notched, as at 40', serves to rotate the valve disk 42—provided with internal projections—by means of the intermediate ring 43 comprising external 110 projections. The valve disk 42 is urged against the polished surface of the member 44 by the action of the spring 45 which abuts against the pin 46 of the driving shaft. In this device, the disk 42 of the valve apparatus is upwardly extended and is pierced with two lateral holes 47 in coincidence with two respective notches 48 of the cap-shaped nut 49 which is held—with the use of a fluidtight packing member 50—upon the valve disk 42, thus allowing the pin 51 to stop the said cap-shaped nut, and to actuate the socket 52 by means of two notches formed therein and engaging the pin 51. In the said socket is formed a safety notch 53 for actuating the above-mentioned auxiliary control; a tapered part 54 forms a rotary valve against the cover of the main body of the valve apparatus during the injection of the carburetted and compressed air; and it assures the absolute 120

fluidtightness of the apparatus during this period. The spring 55 abuts at one end against the said actuating pin, and at the other end it urges the valve upon its seat, which action is also exercised by the air pressure on the said valve. The oil grooves 56 may be formed in the cylindrical part of the valve, to retain the excess of oil.

In Fig. 17, the axle 58 for the auxiliary control, which forms a valve, comprises a double tapered part, thus providing a contact joint at 59 under the effect of the internal pressure when the engine is started, and of the spring of the valve apparatus, or this part may make contact at 60, due to the reaction of the auxiliary control, for example. The device is actuated by the movable socket 61 which is slotted at 62 (Fig. 18) at the upper part, and the drive is also effected by the two projections 63 (Fig. 19) engaging the respective notches 64 in the driving disk. The said notches also serve to stop the cap-shaped nut 65. This device permits bringing the controlling point for the auxiliary control to a point near the joint at the smooth surface of the seating of the valve disk thus obviating as far as possible the prejudicial reactions upon said valve disk due to an eccentric position.

Obviously, the constructional dispositions herein described are given solely by way of example, and the shape, size and material of the several parts may be modified according to circumstances without departing from the spirit of the invention.

Claims:

1. In a valve apparatus for the supply of explosive mixture to the cylinders of internal combustion engines, an actuating axle, a valve disk, a valve seat, a disk having internal and external notches and actuating said valve disk, and a spring outside the actuating axle adapted to apply said valve disk upon said valve seat.

45 2. In a valve apparatus as claimed in claim 1, a valve disk, a cap forming a nut for said disk having holes therein, and a pin traversing one of the holes in the cap and entering a corresponding hole in the valve disk.

50 3. In a valve apparatus as claimed in claim 1, two grooves provided, one within and the other without the friction surface of the valve disk, and valve means associated with said grooves whereby the collecting of condensed gasoline in the valve chamber is prevented.

60 4. In a valve apparatus for the supply of explosive mixture to the cylinders of internal combustion engines, an actuating axle, a valve seat, a valve disk, said actuating axle being adapted to rotate said valve disk, spring means associated with said valve disk for maintaining it against said valve seat, an upward extension on said valve disk, a controlling socket, means connected with

said extension on said valve disk for actuating said controlling socket and against which said controlling socket is pressed to form a fluid tight rotary valve during the supply and compression.

In testimony whereof I affix my signature. 70

LOUIS THOMAS.
